WILLIAM C. CUTLER, OF GLENDALE, CALIFORNIA, ASSIGNOR, BY MESNE ASSIGNMENTS, TO W. M. ARMSTRONG, F. A. McBURNEY, AND F. C. WOLF, TRUSTEES, ALL OF LOS ANGELES, CALIFORNIA.

CENTRAL-DISCHARGE SELECTIVE VENDING MACHINE.

Application filed October 13, 1925. Serial No. 62,254.

The present invention relates to selective vending machines of the type in which a plurality of article holders are revolved about a central point to bring any selected one of the holders into registration with a discharge opening, and the invention has for its principal object the provision of a simple and compact selective vending machine.

Another object of this invention is to improve upon usual machines by placing the discharge chute in spaces ordinarily not occupied, thereby utilizing some of the waste space. In said design the vending mechanism, the discharge chute, and other parts are located below the revoluble magazine and accordingly increase the height of the machine. In said machine there remains a comparatively large central space in which there is contained no parts whatever, and it is an object of this invention to provide for utilizing such space to contain the discharge chute and other parts.

Another object of the invention is to provide room for a slug eliminating coin chute which may extend from the upper part of the machine to the coin controlled operating mechanism; which latter is to be disposed in said central space, without said chute interfering with continued revolving of the magazine of article holders.

Another object of the invention is to provide for using a single closure between the article holders and the discharge chute, which closure is coin controlled and which, when opened, will allow the article which is registered therewith to gravitate into the chute.

A further object of the invention is to provide simple and effective means for accurately centering the magazine just prior to opening movement of the closures, so that the selected article is properly registered with the chute when the closures are moved to open position.

Still other objects and advantages of my invention will appear hereinafter.

I have illustrated my invention by the accompanying drawings, in which:

Figure 1 is a view in front elevation of one practical embodiment of my invention.

Figure 2 is a view in vertical mid-section thereof.

Figure 3 is a view in section seen on a line 3-3 of Fig. 2.

Figure 4 is a view in section seen on a line 55 4-4 of Fig. 2.

In carrying out my invention in the present embodiment I employ inner and outer concentric annular walls 8 and 9 respectively so spaced as to provide for containing a 60 plurality of articles 10, radially disposed with regard to the common center of the said two walls. The articles are shown disposed on edge and both the inner and outer concentric walls are arranged to permit of the 65 articles being moved slidably over the walls.

The inner annular wall provides a circular space 11 which is closed at the front by a removable wall 12, and at the rear by a fixed wall 13. The removable wall carries an integral chute 14 terminating in a narrow opening 15, at the wall 12, which opening will permit of the withdrawal of a single article. The chute curves upwardly and inwardly to terminate in an open article receiving end 16, disposed below the upper part of the inner annular wall.

The inner annular wall is provided with an opening 17 registered with, and conforming closely to, the upper open end of the 80 chute. The chute carries a pair of hinged closures 18 which are hinged to the chute as at 19. Said closures are arranged to fold down into the chute into open position, and when in closed position said closures fill the 85 gap in the inner wall which is provided by the opening 17.

It will be apparent now that as the articles are collectively revolved in their radially disposed positions around the common center 90 of the annular wall, that said articles will successively slide over the closures. The articles which are at any time disposed below the center have their upper ends riding on the outer wall, while those articles which are at any time above center will have their lower ends riding on the inner wall. Obviously, when an article is registered with the closures, said article may gravitate into the chute when the closures are moved to open 95 position.

The machine includes a rear casing wall 21, which is spaced rearwardly of the wall 13 to provide a space 22 in which the slug eliminating coin chute 23 is disposed. Said chute continues upwardly thru said space to a coin slot 24. Said chute, at the lower end turns as at 25 and extends thru the wall 100 105 110

13 into the inner circular space 11, at one side of the chute. The rear casing wall joins the outer annular wall, to co-act therewith, and with the inner annular wall, to enclose the articles. A front wall 26 is provided integrally with the outer annular wall and contains sight openings 27 covered with glass 28 so that the outermost sides of all the articles are visible.

16 The machine includes two spaced rings 29 joined by segmental transverse walls 30 to provide a complete annular article holding magazine; the walls 30 providing individual article holders or pockets 31 open at each end and in each of which an article may be loosely inserted. The magazine is fitted over the inner annular wall and said wall acts as a bearing or axle for same; the magazine being thereby freely revoluble. 20 The outermost ring of the magazine carries an internal ring gear 32 which meshes with a gear 33 which is disposed in the central circular space to one side of the discharge chute. The gear 33 is carried by a shaft 34 and passes thru a bearing 35 in the removable wall 12, to terminate exteriorly in a selecting crank 36. By revolving the crank exteriorly of the machine, any selected article seen thru the sight openings may be moved into registration with the closure; an arrow 37 on the front wall 12 indicating the correct position into which a selected article should be moved. The rear ring of the magazine carries a notched ring 38 provided with teeth 39. The closures are extended rearwardly thru a suitable opening 40 in said wall. Contiguous with wall 13 there is mounted a bar 41 terminating in a point at the lower end so that upon being moved downwardly the point will move between two adjacent teeth and center and lock the magazine. The bar is provided with slots 44, in which are disposed the projecting part of pins 43, carried by the wall 13. Thus the rod is held and guided in vertical movement. The rod is provided with a yoke-slot 42 in which is disposed a pin 45. Said pin is carried by a lever 46 pivoted to the wall 13 as at 47 and curving as at 48 to extend thru slots 49 and 50, in the walls 12 and 13, respectively. Said lever then terminates exteriorly of the casing in a handle 51. By depressing the handle the pin 45 is moved downwardly and acts on the margin of the yoke-slot to force the rod downwardly. The upper end of the rod is bent as at 52, to avoid the rear ends of the closures and carries a lug 53. Said lug is arranged upon downward movement of the rod, to force the closures apart; the rod being so arranged that the closures cannot be opened by any means other than legitimate means, without moving the rod downward. It is understood that where the lever passes thru the circular space it is ordinarily locked

by a coin controlled lock not shown so that the lever, or the closures cannot be moved until a coin has been deposited. In other applications of mine, and throughout the art, numerous forms of coin controlled locks and coin controlled means for rendering operating levers effective or ineffective, are to be found and many such means are applicable to this machine, and therefore no further description of coin controlled means is required herein.

70 It will be apparent now that the part of the circular space 11, which lies to one side of the chute, may contain the gear 32, while the part of space 11 which lies on the other side of the chute may contain coin controlled means for rendering the lever ineffective unless a coin is properly deposited. Thus I have disposed all working parts either in the central space 11 or in the narrow space between the wall 13 and the rear casing wall. The operation of the various parts being practically explained herein, the operation of the machine as a whole may be understood from the following:

75 To purchase an article from the machine the prospective purchaser turns the selecting crank until the article which he has selected is aligned with the arrow. A coin is then deposited within the slot. Until a coin is deposited depression of the operating lever will be fruitless, but when a coin is deposited depression of said lever will move the rod downwardly. First movement of the rod brings the pointed end between two teeth in the toothed ring. When the pointed end is so disposed the magazine cannot be revolved further. As the rod moves further the magazine becomes centered, by the pointed end of the rod, and the closures are moved to open position by the act of the lug being forced between the closures. When the closures have been moved to open position the magazine is accurately positioned and locked so that the article which is registered with the discharge chute is in correct position to gravitate into the chute without interference. The article then slides down the chute to the forward open end, from which it may be taken by the purchaser. Until the lever returns to normal position, the magazine cannot be revolved again. Therefore, only one article may be had for each coin deposited.

80 It will be apparent now that I have provided a selective vending machine in which the parts are compactly disposed and while I have shown and described a specific construction and arrangement of parts, I do not limit myself to any specific construction or arrangement of parts and may alter same as I desire or as occasion requires without enlarging the scope of my invention within the appended claims.

85 Having described my invention, I claim:

1. In a selective vending machine, a vertical casing, an inner annular wall concentric to said casing having its axis horizontally disposed, said wall provided with a discharge opening at the top thereof; and a discharge chute disposed in the space encircled by said wall; said chute having an upper open end registered with said opening. 5
2. In a selective vending machine, a vertical casing, an inner annular wall concentric to said casing having its axis horizontally disposed, said wall provided with a discharge opening at the top thereof; and a discharge chute disposed in the space encircled by said wall; said chute having an upper open end registered with said opening; and movable closures controlling said opening; said wall and closure adapted to allow articles to move slidably thereover. 10
3. In a selective vending machine, a vertical casing, an inner annular wall concentric to said casing having its axis horizontally disposed, said wall provided with a discharge opening at the top thereof and a discharge chute disposed in the space encircled by said wall; said chute having an upper open end registered with said opening; and movable closures controlling said opening; said wall and closure adapted to allow articles to move slidably thereover, and means for collectively moving a plurality of separate articles slidably around said wall and successively over said closure. 15
4. In a selective vending machine, a vertical casing, an inner annular wall concentric to said casing having its axis horizontally disposed, said wall provided with a discharge opening at the top thereof; and a discharge chute disposed in the space encircled by said wall; said chute having an upper open end registered with said opening; and movable closures controlling said opening; said wall and closure adapted to allow articles to move slidably thereover, and means for collectively moving a plurality of separate articles slidably around said wall and successively over said closure, and means housed within said circular space, to one side of said chute, for moving said first named means. 20
5. In a selective vending machine a ring-like magazine provided with open-end radially disposed article-holding pockets, a fixed wall concentrically disposed with regard to said magazine; said wall provided with an upper opening for discharge of an article, said magazine and the contained articles being collectively slidably revolvably around and upon said wall; closures controlling said opening, and a discharge chute registered with said closures and opening; said chute being disposed within the space encircled by said annular wall. 25
6. In a selective vending machine a ring-like magazine provided with open-end ra-
- dially disposed article-holding pockets, a fixed wall concentrically disposed with regard to said magazine; said wall provided with an upper opening for discharge of an article, said magazine and the contained articles being collectively slidably revolvably around and upon said wall, an internal ring gear carried by said magazine, a gear in the space encircled by said concentric fixed wall; said wall provided with an opening thru which the last named gear projects to mesh with said ring gear, and a shaft carrying said last named gear. 70
7. In a selective vending machine, a revoluble annular magazine provided with open-end radially disposed article holding pockets, each adapted to loosely contain an article, an inner concentric fixed annular wall over which the articles are slidable; said wall and magazine having their axes horizontally disposed, an opening in the upper part of said concentric wall, a circular wall closing the forward open end of the space encircled by said concentric wall, a chute carried by said last named wall extending inwardly and upwardly to terminate below said opening, and closures carried by the said upper end of said chute; said closures movable from open to closed position to close said opening; the closures being positioned to allow articles to slide thereover. 80
8. In a selective vending machine, a revoluble annular magazine provided with open-end radially disposed article holding pockets, each adapted to loosely contain an article, an inner concentric fixed annular wall over which the articles are slidable; said wall and magazine having their axes horizontally disposed, an opening in the upper part of said concentric wall, a circular wall closing the forward open end of the space encircled by said concentric wall, a chute carried by said last named wall extending inwardly and upwardly to terminate below said opening, and closures carried by the said upper end of said chute; said closures movable from open to closed position to close said opening; the closures being positioned to allow articles to slide thereover, a second circular wall closing the rear end of the space encircled by said concentric wall; said second circular wall provided with an opening adjacent said closures, rear extensions to said closures extending thru said last named opening, and means behind said second circular wall, operable on the said extensions to move said closures to open position. 90
9. In a selective vending machine, a revoluble annular magazine provided with open-end radially disposed article holding pockets, each adapted to loosely contain an article, an inner concentric fixed annular wall over which the articles are slidable; said wall and magazine having their axes 100
- 110
- 120
- 130

horizontally disposed, an opening in the upper part of said concentric wall, a circular wall closing the forward open end of the space encircled by said concentric wall, a 5 chute carried by said last named wall extending inwardly and upwardly to terminate below said opening, and closures carried by the said upper end of said chute; said closures movable from open to closed 10 position to close said opening; the closures being positioned to allow articles to slide thereover; a second circular wall closing the rear end of the space encircled by said concentric wall; said second circular wall 15 provided with an opening adjacent said clo-

sures, rear extensions to said closures extending thru said last named opening; a concentric annular toothed member at the rear of said magazine, a bar slidably contiguous with said second circular wall, a lug to the upper end of said bar movable to abut the extensions to said closures to move the closures to open position, and a pointed lower end to said bar arranged to enter between teeth of said toothed member coincidentally with movement of said lug.

In testimony whereof I affix my signature.

WILLIAM C. CUTLER.
